UNITED STATES PATENT OFFICE

2,602,436

APPARATUS FOR DRESSING GRINDING WHEELS

Floryan Lohutko, Detroit, Mich., assignor to The Thompson Grinder Company, Springfield, Ohio, a corporation of Ohio

Application December 14, 1948, Serial No. 65,256

3 Claims. (Cl. 125—11)

1

This invention relates to devices for dressing grinding wheels, and particularly to such devices especially adapted for dressing spiral grooves, such as thread forms on the periphery of the grinding wheels.

The grinding of screw threads, gears, and gear cutters requires the grinding wheel to be formed to a high degree of accuracy because this operation on the workpiece is generally the last one to which it is subjected and determines its final accuracy.

Heretofore, grinding wheels have been generally dressed by a diamond dressing tool for this purpose, and ordinarily only a single thread form or a single groove or ridge is formed on a wheel.

This not only increases the length of time which the grinding operation requires since the wheel has only a single form thereon, but also greatly reduces the life of the grinding wheel because of the fact that the entire grinding load is carried by a small area.

Also, the diamond dressing of a grinding wheel does not produce a particularly sharp cutting surface because the diamond shears through both abrasive and bonding material in the wheel and leaves it relatively smooth.

The primary object of the present invention is to provide a device for dressing a grinding wheel which overcomes the foregoing objections and results in a dressed wheel of high accuracy, which has long life and which is exceptionally sharp and fast cutting.

A still further object is to provide a dressing device separate from a grinding machine and wherein blank wheels can be broken down and prepared to the proper form to be ready to be mounted in a grinding machine.

These and other objects and advantages will become more apparent upon reference to the following description taken in connection with the accompanying drawings in which:

Figure 1 is a plan view of a machine constructed according to my invention;

Figure 2 is an end view thereof looking in the direction of the arrow 2 on Figure 1;

Figure 3 is a side elevation of the machine looking in the direction of the arrow 3 on Figure 1;

Figure 4 is a schematic view of one form of hydraulic control circuit for controlling the hydraulic motor associated with the machine;

Figure 5 is a fragmentary view showing a modified construction including an automatic mechanism for feeding the wheel and dressing tool toward each other;

2

Figure 6 is a view looking in at the dressing tool support as indicated by the arrow 6 on Figure 1;

Figure 7 is a sectional view through a control device for regulating the movement of the wheel;

Figure 8 is a diagrammatic electrical control circuit for controlling the several solenoids associated with the valves in the hydraulic circuit of Figure 4; and

Figure 9 is a fragmentary view showing a somewhat modified construction of the machine for employing a different type dressing tool.

Referring to the drawings more in detail, the dressing machine according to this invention generally comprises a bed 10 somewhat L-shaped and mounting on one of its legs a spindle housing 12. A spindle or shaft 14 extends through the housing 12 and is journaled therein at one end by the relatively long sleeve bearings 16. At the other end of the housing there is a nut 18 and keyed to the shaft 14 is a screw 20 threaded to fit the nut 18. It will be apparent that both the screw and nut are removable from the shaft and housing in order to be replaced by another nut and screw having a different thread thereon, if desired.

The left end of the shaft 14, as viewed in Figure 1, is adapted for receiving a grinding wheel supporting block 22 on which is mounted a grinding wheel 24. The mounting of the wheel on the block and the block on the shaft is substantially conventional and is a duplicate of the means for mounting the dressed wheel on the grinding machine in which it will be used.

At the right end of the shaft 14 the said shaft is hollow as at 26 and extending therein is a spindled shaft 28 which is drivingly connected with the shaft 14 by means of a splined sleeve 30. The right end of the spindled shaft 28 is keyed to the output shaft 32 of a reversible hydraulic motor 34. It will be understood that the motor 34 could be of any type and has been illustrated as a reversible hydraulic motor because of the nicety of control which can be exercised over this type of driving device.

Integral with or mounted on the spindled shaft 28 is a gear 36 and meshing with this gear is another gear 38 attached to a shaft 40 which extends into a control box 42. The purpose of the control box, as will be explained hereinafter, is to control the amount of reciprocation given the shaft 14 by rotation of the shaft 32.

On the other leg of the L-shaped bed there is mounted a cylinder block 44 which has a cylinder therein that slidably receives a piston 48. The piston 48 is connected with a rod 50 which is

threaded as at 52 to a nut 54. The nut 54 is retained within a crosshead or plate 56 by the anti-friction bearings 58 and the clamping rings 60. A knurled knob as at 62 is connected with the nut and by means of this knob the nut can be turned relatively to the screw and effect axial adjustment of the piston and rod relative to the crosshead 56. During this adjustment the screw is retained against rotation by the key plate 64 which has a tongue extending into a groove in the threaded portion of the rod 50.

The crosshead 56 is secured to the rearwardly extending arms 66 of a movable platen element 68. The arms 66 are also slidably guided on the cylinder block 44 and thus reciprocation of the piston 48 in the cylinder 46 will also reciprocate the platen element 68.

The platen element mounts a table 70 which is supported on a dove-tail guideway arrangement on the said platen element as indicated at 72 in Figure 2. This arrangement is substantially conventional and there are provided means for adjusting the table 70 along its dove-tail support in the form of a knurled knob 74, a screw 76 driven thereby, and a nut 78 secured to the 25 platen element.

Mounted on the table 70 is a plate 80 which is held in positive alignment with the said table by means of the dowel-pin 82. The plate 80 is rotatable about the dowel-pin 82 within predetermined limits and may be clamped in any position of adjustment within those limits by means of the screw and slot arrangement shown at 84 in Figure 6.

In order to effect a very precise angular adjustment of the plate 80 on the table 70 the said plate has one corner notched out as at 86 in order to expose one corner of the table 70. There is then mounted on this exposed corner of the table 70 an accurately finished dowel 88 and adjacent thereto is an accurately machined arcuate member 90 mounted on the plate 80. By loosening the screws at 84 and inserting precision blocks between the members 88 and 90 in the manner of setting a sine bar, the plate 80 can be adjusted very exactly to any degree of angularity relative to the table 70.

The plate 80 mounts a pair of bearing supports 92 which journal, in any conventional manner, a shaft 94. Mounted on the shaft 94 between the bearing supports is a dressing roll 96 having thereon the configuration which it is desired to transfer to the periphery of the grinding wheel 24.

In the arrangement shown the dressing roll 96 has formed thereon a pair of annular grooves which in cross section are the exact counterpart of a thread form or other gear tooth which is to be ground by the wheel 24. Inasmuch as the grooves in the dressing roll are annular and the groove which it is desired to form on the wheel is to extend spirally therearound, it will be apparent that the mounting of the plate 80 so it can be tilted to an angle relative to the table 70 is an important and essential feature. Furthermore, if the pitch of the groove to be formed on the wheel should change due to a greater size of tooth form or for some other reason, it will be apparent that the position of the plate 80 on the table 70 will have to be further adjusted.

As mentioned before, the drive motor 34 is hydraulic and for supplying power to this motor and also to opposite sides of the piston 48 the hydraulic circuit in Figure 4 may be employed.

In Figure 4 the pump for supply pressure fluid

is indicated at 98 and the suction side thereof is connected with a reservoir 100, while the pressure side thereof is connected with the conduit means 102, one branch of which leads to the inlet of a four-way reversing valve 104 which has its service ports connected as by the conduits 106 and 108 with opposite sides of the piston 48, and which also has exhaust ports connected by the exhaust conduit means 110 with the reservoir 100.

10 The motor 34 has its ports connected with the service ports of a four-way reversing valve 112, the movable part of which is normally centered by the springs 114 so as to interconnect the two ports of the motor with each other and with the exhaust conduits 116 and 118 leading from the valve 112 to the reservoir 100.

The valve 112 also comprises a pressure inlet connected by the conduit 120 with the discharge side of the valve 122 which has its inlet connected with the conduit 102. The valve 122 is a sequencing valve and is normally closed and is adapted for opening upon the establishment for a predetermined pressure on the pilot end 124 thereof by fluid conducted to the said pilot from the conduit 102 by the pilot conduit 126.

20 A spring 128 normally urges the movable element of the valve 104 into position to direct fluid to the upper end of the piston 48 thereby to hold the piston and the frame work connected therewith in retracted position. Energization of a solenoid S3 connected to the said movable member is effective to shift the said member into its other operative position wherein the piston 48 and the frame work associated therewith is shifted in the opposite direction.

30 Similarly, the valve 112 has the solenoids S1 and S2 connected therewith and energization of S1 will shift the movable element of the valve 112 into position to drive the motor 34 in a direction to move the shaft 14 leftwardly from its Figure 1 position. On the other hand, energization of S2 will shift the movable element of the valve 112 into position to drive the shaft 14 rightwardly toward its Figure 1 position.

40 The solenoids S1, S2 and S3 are adapted for being controlled by the control circuit shown in Figure 8 wherein there are the power lines L1 and L2. Between these lines there is connected a contactor coil 130 in series with a normally open push button 132. The push button 132 is by-passed by the normally open blade 134 of the contactor which is in series with the normally closed blade LS1A of a limit switch LS1. The contactor also has a normally open blade 136 which is in series with the solenoid S1 and the parallelly connected solenoid S3.

50 A second contactor 138 is also connected between the power lines L1 and L2 and in series with the normally open blade LS1B of the limit switch LS1. The blade LS1B is by-passed by the normally open contact 140 of the contactor which is in series with a normally open limit switch LS2. The contactor also includes a normally open blade 142 which is in series with the solenoid S2.

60 There is also provided a normally closed limit switch LS3 in series with the contactor 130 which is adapted for being opened by engagement with the wheel supporting member 22 for halting operation of the motor 34 in event the said wheel should be driven beyond its normal limits of travel.

70 The limit switches LS1 and LS2 are mounted within the control unit 42 as shown in Figure 7. In this figure it will be noted that the shaft 40 is

threaded internally of the unit and mounts a cam block 144 which is adapted in its left hand position for engaging and opening the limit switch LS2 and in its right hand for engaging the limit switch LS1 thereby to open the blade LS1A thereof and to close the blade LS1B thereof.

Should it be desired to provide for an automatic in-feed of the dressing roll toward the wheel axis, the nut 54 may have connected therewith a ratchet wheel 146. This wheel is adapted for being engaged by a pawl 148 carried on a piston rod 150 which is connected with a piston 152 in a cylinder 154. The cylinder 154 is connected with a four-way reversing valve 156 which is urged into one operative position by a spring 158 and into another by energization of a solenoid S4.

The solenoid S4 is connected as shown in Figure 8 in parallel with the solenoids S1 and S3 and through a selector switch 160 which can be closed to make the automatic in-feed mechanism operative and opened to make the said mechanism inoperative.

Operation

In operation, a wheel to be dressed is mounted on the wheel supporting block 22 and secured thereto in the usual manner. At that time the shaft 14 occupies its Figure 1 position and the dressing roll 96 will also occupy its Figure 1 position, wherein it is retracted from the periphery of the wheel 24.

A dressing cycle is commenced by closing the switch 132 which energizes the contactor 130 and therethrough energizes the solenoids S1 and S3. Energization of S1 will shift the movable element of the valve 112 into position to supply pressure fluid to the motor 34 to drive it in a direction to advance the shaft 14 leftwardly. At the same time the solenoid S3 shifts the movable element of the valve 104 into position to direct pressure fluid to the lower side of the piston 48 thereby to move the said piston and the structure associated therewith toward the wheel axis. This positions a dressing roll in proper relationship to the periphery of the grinding wheel.

It will be noted that at this time the piston and the frame work connected therewith will be completely shifted before the motor 34 commences to operate due to the sequencing valve 122 which requires that a predetermined pressure be built up in the conduit greater than that required to shift the piston 48 and the mechanism driven thereby before the said valve will open to admit pressure fluid to the motor 34.

Also, during operation of the motor 34 for driving the shaft 14 leftwardly, the throttle valve 162 may be adjusted for controlling the speed of operation of the said motor thereby to maintain the peripheral speed of the grinding wheel within the proper limits.

As the motor 34 drives the shaft 14 into rotation and reciprocation, the threaded shaft 40 is also driven and carries the block 144 toward the limit switch LS1. When the block reaches the said switch, and the position of the switch has been predetermined by adjusting its position by the rod 164, the said switch is actuated to open the blade LS1A, thereby to deenergize the contactor 130, and therethrough to deenergize the solenoids S1 and S3 and to close the blade LS1B thereof, thereby to energize the contactor 138, and therethrough to energize the solenoid S2. At this time the piston 48 and the mechanism driven thereby retract from the wheel axis and the motor 34 is reversed to retract the wheel 75

to its starting position. When the wheel has reached its starting position the cam 144 will engage the limit switch LS2 and open the same and thereby de-energize the contactor 138, and thereby de-energize the solenoid S2.

If the selector switch 160 is closed at the time the push button 132 is closed then an automatic in-feed of the dressing roll takes place of a predetermined amount. If the selector switch 160 is not closed then the dressing roll can be fed in by manual operation of the knurled hand wheel 62.

The embodiment described above utilizes a crushing roll type dressing tool and it will be apparent that such a dressing roll can be mounted for free rotation and that it will automatically properly align with the wheel being dressed. Should it be desired to employ a cutting or picking type tool, then the said tool may be driven in synchronism with the grinding wheel. An arrangement of this type is illustrated in Figure 9 wherein the dressing roll 96 is replaced by a cutting or picking type dressing roll 166 and the supporting shaft 168 thereof is connected through the universal joints 170 and shaft 172 with the geared take-off 174 leading from the driven gear 36.

By this arrangement the wheel and dressing tool are always positively synchronized and thus each time the wheel reciprocates into engagement with the dressing tool it will engage therewith in the proper manner.

The dressing tool shown in Figure 9 is, of course, tiltable as is the dressing roll shown in Figure 1, and is advanced toward the wheel axis and retracted therefrom in synchronism with the reciprocation of the said wheel.

It will be understood that this invention is susceptible to modification in order to adapt it to different usages and conditions and, accordingly, it is desired to comprehend such modifications within this invention as may fall within the scope of the appended claims.

I claim:

- 45 1. In combination in a device for dressing a grinding wheel; a bed, a spindle housing on said bed, a shaft extending through said housing and having a bearing support at one end thereof and a screw threaded support at the other end thereof; mounting means for a wheel to be dressed on the said one end of said shaft, a fluid operable motor splined to the other end of said shaft whereby energization of said motor will bring about rotary and axial movement of said shaft and of a wheel mounted thereon, an annularly ribbed crush dressing roller tiltably mounted on said bed, fluid operable piston means operably connected with said roller for moving said roller in one direction to place it in operative alignment with the periphery of a wheel carried by said shaft and to retract it from operative alignment with said wheel, interconnected reversing valve control means having conduits connecting the said valve control means with said fluid motor and said piston means, said valve control means being operable for energizing said motor for one direction of rotation and said fluid operable means to move said roller into operative position and also operable to reverse said motor and to operate said fluid operable means to retract said roller from said operative position, and means responsive to a predetermined travel of said motor while said roller is in retracted position for automatically de-energizing said motor.
- 50
- 55
- 60
- 65
- 70

2. In a device for dressing a grinding wheel; a bed, a spindle housing on said bed, a shaft in said housing having means at one end to receive a wheel to be dressed, screw means at the other end of said shaft whereby rotation of the shaft will produce axial movement thereof, a hydraulic motor splined to said shaft for driving it in rotation, a crush dressing roll rotatably mounted on said bed adjacent the wheel end of said shaft for intimate pressured engagement with said wheel, fluid driven piston means operably connected with said roll to advance said roll into the path of the periphery of said wheel and to retract the roll from said wheel, and control means including solenoid operated fluid passing valves having conduits connecting the valves with said hydraulic motor and said piston, said valves being operable to control the energization of said motor and direction of fluid flow in said piston means to advance and retract said roll.

3. In combination in a device for dressing a grinding wheel; a bed, a spindle housing on said bed, a shaft extending through said housing and having a bearing support at one end thereof and a screw threaded support at the other end thereof, mounting means for a wheel to be dressed on the said one end of said shaft, a fluid operable motor splined to the other end of said shaft whereby energization of said motor will bring about rotary and axial movement of said shaft and of a wheel mounted thereon, an annular ribbed crush dressing roller tiltably mounted on said bed for intimate pressured engagement with said wheel, fluid operable piston means operably connected with said roller for moving said roller in one direction to place it in operative alignment with the periphery of said wheel carried by said shaft and to retract it from operative alignment with said

wheel, interconnected reversing valve control means having conduits connecting the said valve means with said fluid motor and said piston means, said valve means being operable for energizing said motor for one direction of rotation and said fluid operable means to move said roller into operative position, and an electric circuit arrangement including solenoids operably connected with said valve means operable to reverse said motor and to operate said fluid operable means to retract said roller from said operative position.
